VEHICULAR SAFETY DEVICE OR THE LIKE

Kenneth D. Kramb, Portage, and Walter J. Isabell, Kalamazoo, Mich., assignors to K.I.C. Incorporated, Portage, Mich.

Filed Nov. 13, 1972, Ser. No. 305,857

Term of patent 14 years

Int. Cl. D12—16

U.S. Cl. D12—199

FIG. 1

FIG. 3

FIG. 2

FIG. 1 is a front perspective view of our vehicular safety device or the like showing our new design;

FIG. 2 is a rear elevational view of our vehicular safety device or the like; and

FIG. 3 is a top plan view of our vehicular safety device or the like.

The vehicular safety device, or the like, is mounted to the hood or similar element of a vehicle, such as a snowmobile, for the snagging, cutting, or breaking of wire, rope, or the like.

We claim:

An ornamental design for a vehicular safety device or the like, substantially as shown and described.
